LOOSE-LEAF SHEET CALENDAR HANGER

Orion P. Winford, St. Paul, Minn., assignor to
 Brown & Bigelow, St. Paul, Minn., a corporation
 of Minnesota

Application March 26, 1951, Serial No. 217,462

7 Claims. (Cl. 283—2)

1

My invention relates to an improvement in a loose-leaf calendar and more particularly to the novel construction for removably supporting the loose-leaf sheets thereof as a calendar hanger.

It is a feature of my invention to provide a support for loose-leaf calendar sheets which is formed from an extension of the top portion of the back member of the calendar.

It is a feature to provide an extension of the back member of the calendar, the outermost portion of which is folded and inserted through a slot or slit formed in each of the sheets to be mounted and then further inserted through a slot formed in the back member which aligns with the slots of the sheets. The extension is then folded upwardly and against the rear surface of the back sheet member to removably bind the sheets to the back member. This construction is aided and accomplished by forming fold lines in the upper extension of the back sheet member intermediate the outermost extension and the slot or slit formed in the back sheet member, in addition to fold lines formed intermediate the aforementioned fold lines and the outermost extension.

It is also a feature to provide a top flat member which maintains the upper edges of the mounted loose-leaf sheets in a relatively flat position. It is a further feature to provide a pocket formed on the bottom portion of the loose-leaf calendar sheets.

It is an additional feature to provide a series of loose-leaf sheets each of which has a transverse slot or small opening formed therein adjacent the upper edge thereof which receives the outermost extension of the backing sheet and is thereby removably supported against the back support sheet member.

With my construction for calendar hangers, the loose-leaf sheets thereof may be easily mounted, removed, rearranged or discarded.

It is also a feature to provide a calendar loose-leaf sheet support whereby the support member is formed in one piece with the back member.

The invention will appear clearly from the following detailed description when taken in connection with the accompanying drawings, showing by way of example a preferred embodiment of the inventive idea.

In the drawings forming part of this application:

2

Figure 1 is a perspective view of my calendar with the bottom end of the sheets thereof slightly upturned.

Figure 2 is a plan view of the back sheet support member in died-out form.

Figure 3 is a plan view of a died-out alternative form of the back sheet support member.

Figure 4 is a plan view of a loose-leaf sheet of my calendar.

10 Figure 5 is a plan view of a loose-leaf sheet of my calendar having an end portion thereon adapted to be constructed as a pocket on the sheet.

Figure 6 is a partially enlarged section on the line 6—6 of Figure 1.

Figure 7 is a partially enlarged section on the line 7—7 of Figure 1.

My loose-leaf sheet calendar hanger A is composed of a back sheet support member 10, which has formed on the upper end thereof a foldable extension binder member consisting of the transverse extended portion 11, and the further outermost tongue extension portion 12, which is integrally formed with the extension portion 11.

25 The tongue extension portion 11 may be formed integrally with the back sheet support member 10. The extension portion of the calendar is formed of the extended portions 11 and 12, folded into the position shown in Figure 6 by means of the scored or fold lines 13 and the further scored or fold lines 14.

The back sheet support member 10 has formed therein the transverse slot or opening 15 through which the outermost extension 12 is inserted with the sheets supported by the portion separated by the fold lines 14, which portion I indicate as 14'. For hanging the back sheet support member 10, I provide the hole 16 through the end of the extension 12 which is adapted to receive a nail or hook or any other suitable means to hang the calendar back sheet support member 10.

I further provide loose-leaf sheets in the form of the sheet 17, which has formed therein the transverse slot or opening 18. A day of the month calendar may be imprinted on the face of the sheet 17. I provide another type of loose-leaf sheet 19 which has the transverse slot or opening 20 formed therein, and which also has the lower depending member 21 which is folded and secured to form a pocket 22 as illustrated more particularly in Figure 1. Either type of

sheet, 17 or 19, may be used with my calendar hanger A.

The lower depending portion 21 has formed on the sides thereof the extended flange portions 23 which are folded on the lines 23' and secured to the back surface of the sheet 19 when the depending portion 21 is folded upwardly against the front surface of the sheet 19 on the fold line 24, thereby forming the pocket 22.

In assembling my loose-leaf sheet calendar, the sheets 17 or 19 are placed upon the back sheet support member so that the slots 18 or 20 align with the slot or opening 15. The outer tongue extension member 12 is then folded on the fold line 14 and the extension portion 11 is folded on the fold line 13 while the tongue extension portion 12 is inserted through the opening 20, for example, and then through the slot 15, the tongue extension portion being folded up against the back surface of the back sheet support member 10 to assume the position shown in Figure 6 and Figure 1. Sheet 19 may be removed or released by pulling the extension 12 out through the slot 15 and also from the slot 20.

With my construction the sheets, such as 19, may be removed or rearranged very simply and without turning the pocket 22 upside down in changing the sheets 19. Further, with my construction, the calendar support with loose-leaf sheets may be very easily and economically made, for the back sheet support member 10 together with the extension portions 11 and 12 may be made of heavy grade paper. In addition, the extension portion 11 serves to hold down the upper ends of the sheets 19 as a binder therefor, particularly illustrated in Figure 1 of the drawings. Advertising indicia may be placed on the outer surface of the sheets 19 or 17 in conjunction with the calendar indicia illustrated on the outer portion of the pocket 22, as illustrated in Figure 1. With my simple loose-leaf sheet calendar with the pockets 22 on the sheets 19, the sheets may be removed and placed to the rear of the series or pack of sheets for future reference. The pockets 22 may be used to file recipes and notes therein for future use. The sheets, such as 19, with the current calendar month thereon is supported as the first sheet and thereby fully visible.

I provide an alternative back sheet support member 25 which is similar to the upper portion of the back sheet support member 10 but which does not have the extended sheet portion as illustrated in Figure 2, which extended portion is not absolutely necessary for the support and hanging of my loose-leaf calendar sheets such as 17 and 19.

It is apparent that my support member need not necessarily be formed with the fold lines 13 and 14 but may be provided with a single fold line 13 and/or 14.

I have provided in my new calendar hanger construction a relatively long transverse opening 15 together with a relatively long coinciding slot 18 or 20 through which the relatively wide extension portion 12 is adapted to be inserted. The width of the extension portion may be of any dimension. However, when it is relatively wide, the sheets are held more compactly and one directly over the other and the same do not tend to angle in relation to each other or in relation to the back sheet support member 10.

The invention is not to be understood as restricted to the details set forth since these may be modified within the scope of the appended

claims without departing from the spirit and scope of the invention.

Having thus described the invention, what I claim as new and desire to secure by Letters Patent is:

1. In a loose-leaf calendar, a support member, an extension connected to said support member, said support member having an opening formed therein, a series of loose-leaf sheets having openings formed therein and adapted to align with said support member opening, all of said openings adapted to receive said extension therethrough to hold said sheets to said support member with said extension drawn upwardly against the back surface of said support member to bind said sheets and provide a hanger therefor.

2. In a calendar hanger, a support member having an opening formed therein, a series of loose-leaf sheets having openings formed therein, extension binder means formed on said support member adapted to be inserted through said openings of said sheets and said opening formed in said support member to form a hanger for said sheets and removably bind the same to said support member.

3. A loose-leaf removable sheet calendar hanger consisting of a series of loose-leaf sheets, each having an opening formed therein, a support member having an opening coinciding with said opening in each of said sheets and means extending from said support member and positioned through said openings of said sheets and said opening of said support member to bind together and support said series of sheets one upon the other.

4. A loose-leaf calendar comprising a series of sheets, calendar indicia formed on the bottom of each sheet, a long horizontal slot formed near the top of each sheet, a paper binder and sheet retainer means having a projecting tongue from one edge thereof and a horizontal slot formed therein adapted to coincide with the slots formed in said sheets, said binder means being adapted to be folded over the top edges of said calendar sheets and said tongue being adapted to extend through said openings in said sheets and in said binder member to provide a hanger and binder for the top edge of said sheets.

5. A loose-leaf calendar including a series of calendar sheets each having monthly indicia thereon, a horizontal slot formed marginally near the top of each of said sheets, a binder and support member for the top edge of said sheets having a back portion which is positioned as the back of said sheets and a complementary slot formed therein, a tongue projecting from said back member and a binding portion formed on said back member between the body of said back and said tongue and adapted to be folded over the top edge of said calendar sheets to bind the sheets together when said tongue passes through said slots in said sheets and through said slot in said back member, said tongue being adapted to project above the binder portion of said back sheet to act as a hanger for said calendar.

6. A loose-leaf calendar comprising a series of individual calendar sheets, each of said sheets having a long horizontal slot formed near the top edge thereof and a support and binder means folded on the top thereof to extend over the top edge of said sheets and down a portion of the front thereof to hold the same bound together, including a hanger tongue formed on said support and binder means adapted to extend through 75 said slots and through a coinciding slot formed

in said binder member to provide a hanger for said calendar.

7. A loose-leaf calendar including a support member, a series of loose-leaf sheets each having an opening formed therethrough, an extended binder portion formed on said support member, a tongue extension member formed on said extended binder portion, said support member having an opening formed therethrough adapted to align with said openings of said sheets, said binder portion folded downwardly upon said sheets, and said tongue extension inserted through said slots of said sheets and said slot of said support member, and formed in an up-

wardly extending manner against said support member to form a hanger for said calendar and secure said binder member against said sheets to removably bind said sheets together.
